UNITED STATES PATENT OFFICE.

THOMAS S. OBEAR, OF ST. LOUIS, MISSOURI.

DESIGN FOR A BOTTLE.

No. 38,835.

Specification for Design.

Patented Sept. 24, 1907.

Application filed August 28, 1907. Serial No. 390,553. Term of patent 14 years.

To all whom it may concern:

Be it known that I, THOMAS S. OBEAR, a citizen of the United States, and a resident of the city of St. Louis and State of Missouri, have invented a new, original, and ornamental Design for a Bottle, of which the following is a specification.

In the accompanying drawing, which forms part of this specification, Figure 1 is a side elevation of a bottle embodying my design; Fig. 2 is a similar view on the opposite side of the bottle; and, Fig. 3 is a top plan view thereof.

What I claim is:

The ornamental design for a bottle, as shown.
